UNITED STATES PATENT OFFICE.

AUGUST BUNGER, OF HOBOKEN, NEW JERSEY.

PRINTING-PRESS FOOT OR SUCKER.

Application filed January 22, 1923. Serial No. 614,314.

To all whom it may concern:

Be it known that I, AUGUST BUNGER, a citizen of the United States, residing at Hoboken, in the county of Hudson and State 5 of New Jersey, have invented certain new and useful Improvements in Printing-Press Feet or Suckers; and I do hereby declare the following to be a full, clear, and exact description of the invention, such as 10 will enable others skilled in the art to which it appertains to make and use the same.

The object of the invention is to provide an improved construction of suction feet for use in connection with the conventional 15 form of separator bar to lift the uppermost sheet from the stock pile or rack of a printing press for engagement by the gripper of the feet frame to be carried forward over the platen, and particularly to provide a 20 construction of suction feet or suckers as they are called whereby the variation or graduation of the suction applied to the feet through the valve mechanism or the equivalent thereof may be avoided and also 25 whereby the substitution of different types or constructions of suction feet in operating on paper of different thicknesses may be avoided, to the end that a single set of suction feet may be used in connection with 30 all thicknesses of paper and cardboard and will operate as effectively in lifting a single sheet of very thin paper as with the heavier grade encountered in connection with general work in the printing art; and 35 with this object in view the invention consists in a construction, combination and relation of parts of which a preferred embodiment is shown in the accompanying drawings, wherein:

40 Figure 1 is a sectional view of a typical form of printing press to show the location of the separator bar by which suction or pneumatic feet embodying the invention are carried,

45 Figure 2 is an inverted plan view of the separator bar showing the suction feet applied thereto, to show the faces or operative surfaces of the suction feet, a series of which include two side feet and an intermediate foot,

50 Figure 3 is a detail perspective view of one of the side suckers, the same being inverted,

Figure 4 is a similar view showing a suc-

tion reducing bridging web applied to the 55 sucker foot illustrated in Figure 3,

Figure 5 is a view similar to Figure 3 but showing an intermediate foot,

Figure 6 is a longitudinal sectional view 60 of a sucker foot constructed in accordance with my invention and equipped with a suction reducing bridging web adapting the foot for operation upon very light paper as tissue,

Figure 7 is a similar view with the web 65 removed adapting the foot for operation on a heavier grade of paper,

Figure 8 is a view similar to Figure 7 showing the opening in the suction tube closed, whereby suction of the foot is increased to permit of the suction foot operating upon a heavier grade of paper,

Figure 9 is a view similar to Figure 8 showing the primary filler block in place thereby still further increasing the suction, and

Figure 10 is a view similar to Figure 8 showing both the primary and secondary 80 filler blocks in place, the sucker foot as here shown being adapted for operation on a very heavy grade of paper or cardboard.

The pneumatic or suction feet embodying the essential feature of the invention are 85 preferably arranged in a series consisting of the intermediate foot 10 and the terminal or side feet 11 carried by the separator bar 12 which is of conventional form and is movable toward and from the pile of stock 13 for the purpose of raising the topmost sheet to be carried by the feed 90 frame 14 into position on the platen 15, and in the usual practice with each suction foot there is connected a suction tube 16 for creating suction at the under or operative 95 face of the foot through one or more openings 17 in the foot.

In the construction of foot herein disclosed the face is provided with a plurality of parallel shallow flat faced ribs 18 spaced apart and arranged preferably in parallelism, as indicated, upon opposite sides of the suction opening 17 in the foot. The employment of the ribs obviously provide air passages 21 between the bottom of the feet and the surface of the sheet of paper 105 upon which they rest. These passages permit a sufficient amount of air to pass above the sheet into the openings 17 to prevent

the full force of the suction applied through the tubes 16 being applied to the paper upon which the feet rest.

In addition it is proposed to provide in 5 the suction tubes inlet orifices or vents 23 which still further break the suction.

As a means of further reducing the suction applied to the suction feet thin strips or webs of paper 20 or the like are, as shown 10 in Figures 4 and 6, detachably secured in position to bridge the air spaces 21, and they are secured to the ribs 18 by paste or the like. The webs 20 serve to space the ribs 18 from the surface of the sheet which 15 is being acted on, and in view thereof and when the orifices or vents 23 are open air will pass into the tubes through the orifices or vents, and between the bottoms of the feet and the surface of the sheet and 20 over the bridges 20 into the openings 17.

When the sucker feet are equipped as last 25 stated and as illustrated in Figures 4 and 6, they are adapted for operation on the very thinnest type of paper, such as tissue. It is to be understood that the showing in 30 Figure 4 of the application of the bridging web 20 to the side feet is also illustrative of the manner in which the same is to be applied to the center sucker foot.

When a heavier or second grade of paper 35 is to be handled, the suction may be increased by removing the webs 20 to provide the structure previously described and illustrated in Figure 7.

To adapt the feet for the handling of a 40 third or still heavier grade of paper, it is but necessary to plug or stop the orifices or vents 23 and omit the webs 20, as shown in Figure 8.

Filler blocks 26 and 27 to which reference hereinafter will be made as primary and secondary filler blocks are adapted to be positioned in the top walls of the air passages 45 21 of the suction feet and are adapted to be respectively arranged in rear and in front of the suction openings 17, as illustrated in Figures 9 and 10 of the drawings. When the filler blocks 26 are in place, as shown in Figure 9, the amount of air that may enter 50 the openings 17 over the sheet of paper is still further cut off and the stress or force of the suction is thereby increased upon the paper sheet, and the device is therefore adapted for operation upon the fourth grade 55 or still heavier grade of paper which owing to its thickness and weight requires a greater amount of suction in order that it may be lifted effectively to be engaged by the grippers of the feed frame. To still 60 further increase the suction or the effect of the suction so as to adapt the feet for operating on a still heavier grade of paper the secondary filler blocks 27 are arranged in place as shown in Figure 10, thereby entirely cutting off the inlet of air to the open-

ing 17 over the sheet, and as the result permitting the full force of the suction to be utilized in lifting the sheet.

Each of the feet 10 and 11 has its outer edge formed or provided with a depression 70 28 into which the suction openings 17 extend. The object of the depression is to provide a means to prevent the sucker feet lifting more than one sheet of paper at a time, should the paper be of such a nature 75 as to permit the suction being effected through the top sheet on to the next sheet. In operation, when suction is applied to the paper through the suction opening or openings in the suction feet, the top sheet of 80 paper of the pile will have a portion thereof drawn into the depressions 28 and thus an air space will be provided between the top and second sheets of paper which will break the partial vacuum created between the first and second sheets and release the second sheet from the suction of the foot. It is to be noted that the depression entirely surrounds the suction opening in the foot and 85 will thereby obviate any possibility of the suction being effective on more than one sheet of paper.

Heretofore, in the employment of sucker feet it has been the practice to use three sets 90 of feet for different thicknesses and weights of paper and in addition to the employment of the three sets of feet, there has been provided a valve mechanism to regulate the stress of suction applied through the feet. The use of my invention obviates the necessity 95 for the three sets of feet and the pressure regulating valve mechanism. With a foot of the type herein set forth it is possible without any manipulation of valve mechanism to adapt it for lifting paper 100 varying in thickness from the thinnest sheet of tissue to a six-ply sheet of cardboard, and as the filler blocks may consist merely of cardboard secured in place by paste or adhesive of any preferred kind, 105 it is obvious that the same can be made readily and without loss of time. Furthermore this construction avoids the necessity 110 of employing different sets of suction feet in connection with a press and the loss of time incident to making a change in the application of the feet when it is desired to change the grade of paper. In addition to the above different permutations of the attachable elements may be worked out to 115 provide for a very fine adjustment of the suction applied through the sucker feet.

Having thus described the invention, what I claim as new is:—

1. A sheet separating and gripping mechanism for printing presses having suction feet having suction openings and connected suction tubes provided with vents for modifying the force of the suction and means for obstructing said vents. 130

2. A suction foot for the purpose indicated having a suction opening and spaced ribs forming a channel in communication with the suction opening and means for obstructing said channel.
3. A suction foot for the purpose indicated having a suction opening and parallel projecting ribs defining a channel in communication with the suction opening and spanned by a flexible web.
4. A suction foot for the purpose indicated having a suction opening and its face provided with spaced ribs defining channels in communication with the suction opening, and primary and secondary filler blocks for arrangement in obstructing relation with said channels.
5. A suction foot having a suction opening and spaced ribs forming channels in communication with the suction opening.
6. A suction foot having a suction opening and spaced flat faced ribs forming a channel in communication with the suction opening.
7. A suction foot having a suction opening and parallel projecting ribs defining a channel in communication with the suction opening, and a bridging web adapted to span said ribs.
8. A suction foot for the purpose indicated having a suction opening and parallel projecting ribs defining a channel in communication with the suction opening, and a bridging web adapted to span said ribs at one side of the suction opening.
9. A suction foot for the purpose indicated having a suction opening and parallel projecting ribs defining a channel in communication with the suction opening, a bridging web adapted to span said projecting ribs, and filler blocks adapted to be arranged in said channel at opposite sides of the suction opening.
10. A suction foot for the purpose indicated having a suction opening and parallel projecting ribs defining a channel in communication with the suction opening, and primary and secondary filler blocks adapted to be arranged at opposite sides of said opening in obstructing relation with said channel.
11. A suction foot having a suction opening, means to modify the force of the suction through the opening, and means bridging the first mentioned means and attachable thereto to further modify the force of the suction.
12. A suction foot having a suction opening, means integral with the face of the foot to modify the force of suction through the opening, and other means bridging the first mentioned means and attachable thereto to further modify the force of the suction.

In testimony whereof I affix my signature in presence of two witnesses.

AUGUST BUNGER.
